UNITED STATES PATENT OFFICE.

WILLIAM M. REICHART, OF CLEVELAND, OHIO, ASSIGNOR TO THE CHANDLER & PRICE COMPANY, OF CLEVELAND, OHIO, A CORPORATION OF OHIO.

INKING ROLL FOR PRINTING PRESSES.

Application filed September 19, 1921. Serial No. 501,564.

To all whom it may concern:

Be it known that I, WILLIAM M. REICHART, a citizen of the United States, and a resident of Cleveland, county of Cuyahoga, 5 and State of Ohio, have invented a new and useful Improvement in Inking Rolls for Printing Presses, of which the following is a specification, the principle of the invention being herein explained and the best 10 mode in which I have contemplated applying that principle, so as to distinguish it from other inventions.

The inking rolls used in printing presses, as is well known, are formed of a special, 15 more or less resilient, composition, and due to the character of such composition it is not only difficult to insure uniform diameter of said rolls in the manufacture of same, but such diameter is apt to change under 20 conditions of use. Inasmuch as the rolls in the course of their passage over the form are supported on metal rollers running on tracks, or equivalent supports, such rollers being ordinarily merely the exposed ends of 25 the metal base to which the aforesaid composition material is attached, it will be seen that any variation in the diameter of the roll itself will cause a variation in the pressure with which it contacts with the form. 30 This of course is objectionable for reasons that need not be detailed, and the object of the present invention, accordingly, is the provision of means in the nature of an adjustable roller on the ends of such inking roll whereby the latter may be caused to 35 bear with uniform pressure despite changes in diameter.

To the accomplishment of the foregoing and related ends, said invention, then, 40 consists of the means hereinafter fully described and particularly pointed out in the claims, the annexed drawing and the following description setting forth in detail certain mechanism embodying the invention, such 45 disclosed means constituting, however, but one of various mechanical forms in which the principle of the invention may be used.

In said annexed drawing:

Fig. 1 is a broken elevational view of an 50 inking roll of the class described, one end thereof and the corresponding supporting roller being shown in axial cross-section; Fig. 2 is a view similar to Fig. 1, but showing only one end of the inking roll and adjacent supporting roller, the latter being

shown in different adjusted position; and Fig. 3 is a transverse section through such supporting roll, the plane of the section being indicated by the line 3—3, Fig. 1.

As illustrated in Figs. 1 and 2, the inking 60 roller is shown as passing over the form 1, which is supported on the bed 2 of the press. It is a matter of indifference of course whether the latter be of the so-called Gordon or platen type, although the swing arms 3, to which the ends of the roll are shown as being attached, are characteristic of such type. The roller itself comprises a metallic core 4, the body of which is surrounded by a layer 5 of the composition previously referred to, such core being mounted upon a spindle 6, the ends of which are rotatably held in or otherwise attached to the ends of arms 3.

The rollers for supporting the inking roll 70 are mounted on such spindle ends, between the ends of the core 4 and the adjacent arm 3, and travel on tracks 9 on the bed 2, as shown in Figs. 1 and 2. Each such roller is built up of a sleeve 10, keyed or otherwise 75 non-rotatably secured to spindle 6, and formed at its inner end with a beveled flange 11. Threaded on the sleeve 10 is a second sleeve 12 that is formed with a flange 13 beveled oppositely to flange 11 so that when 80 the two parts just described are assembled a V-shaped groove is formed therebetween. Suitable means are provided for locking the two sleeves together in adjusted longitudinal position relative to each other, changes 85 in such position varying the width of the V-shaped groove just referred to. Such means, as shown in the drawing, comprise the longitudinal keyways or grooves 14, formed in the inner sleeve, which are adapted 90 to be engaged by pins, or screw studs, not shown, which may be inserted in the radial apertures 14^a formed in the outer sleeve, as is shown in Fig. 1.

Mounted in the V-shaped groove between 100 the beveled flanges 11 and 13 is an annular member or rim 15, which may, if desired, be provided with a tire 16 of hard rubber or like material such rim having its lateral faces beveled to correspond with said flanges 105 11 and 13. A radial pin 17 is tightly fitted in sleeve 10 adjacent flange 11 and engages a recess 18 in the inner face of said member 15, whereby the latter is caused to rotate uniformly with said sleeve and so in turn 110

to impart a positive rotative movement to the roll, as is desirable. In other words, said pin acts as a sort of key, the recess 18, however, being large enough to permit of 5 the relative movement of the parts herein-after set forth.

From the foregoing description it will be seen that when the sleeves 10 and 12 are adjusted so as to bring the flanges 11 and 13 10 as closely together as possible the rim 15 will be held fixedly therebetween, but upon moving flange 13 away from flange 11, and correspondingly widening the groove there-between the rim will be more or less loosely 15 seated in such groove. Depending upon the width of the latter, the portion of such rim in contact with the track 9 will be forced radially inward toward the spindle, as shown in Fig. 2, with the result that the 20 effective diameter, or rather radius, of the roller is correspondingly decreased. In this condition of the parts, the rim will have a rolling movement in the groove, but its effective radius, i. e., that between the portion 25 of the surface that contacts with the track and the axis of the spindle, will at all times remain the same. It will be understood of course that the rolls 3 are necessarily under spring, or other tension, which 30 serves to pull the inking roll towards the form, the function of the supporting rollers being simply to limit such pulling action and to cause the roller to rotate as it passes across the form without relying on the 35 rotative effect produced by direct contact of the roll itself with the form.

The foregoing construction provides an exceedingly simple and ready means for adjusting the pressure with which the inking 40 roll is thus held against the form, and changes in the diameter of such roll may be readily compensated for by rotating the outer sleeve 12 on the inner sleeve 10 so as to vary the width of the groove between the

respective beveled flanges carried by such 45 sleeves, and thus allowing the rim of the roller to enter such groove more or less as occasion demands.

Other modes of applying the principle of my invention may be employed instead of 50 the one explained, change being made as regards the mechanism herein disclosed, provided the means stated by any of the following claims or the equivalent of such stated 55 means be employed.

I therefore particularly point out and distinctly claim as my invention:—

1. In an inking roll for a printing press, the combination with the roll spindle, of a 60 roller for said spindle, said roller including a rim of fixed diameter surrounding said spindle, means for supporting said rim on said spindle, said means being adjustable thus variously to support said rim from concentric relation to said spindle to variable degrees of eccentricity therewith, and means restraining rotative movement of said rim about said spindle. 65

2. In an inking roll for a printing press, the combination with the roll spindle, of a 70 roller for said spindle, said roller including a rim of fixed diameter surrounding said spindle, oppositely beveled flanges on said spindle between which said rim is supported, said flanges being relatively adjustable 75 longitudinally of said spindle, whereby said rim may be thus variously supported from concentric relation to said spindle to variable degrees of eccentricity therewith, and a radially projecting pin fixed with respect to said spindle and having loose engagement with said rim, whereby rotative movement of said rim about said spindle is restrained. 80

Signed by me, this 12 day of September, 85
1921.

WILLIAM M. REICHART.
